[57] **CLAIM**

The ornamental design for a video display pedestal, as shown and described.

DESCRIPTION

FIG. 1 is a perspective view of a video display pedestal showing my new design;

FIG. 2 is a front elevational view thereof;

FIG. 3 is a left side elevational view thereof, the right side elevational view and the rear elevational view being a mirror image thereof;

FIG. 4 is a top plan view thereof; and,

FIG. 5 is a front perspective view thereof, on a reduced scale, the broken line drawing of a video display unit being shown for illustrative purposes only and forms no part of the claimed design.

The underside of the video display pedestal is not ornamented.
